HERBERT T. HERR, OF PHILADELPHIA, PENNSYLVANIA, ASSIGNOR TO WESTINGHOUSE ELECTRIC AND MANUFACTURING COMPANY, A CORPORATION OF PENNSYLVANIA.

NOZZLE BLOCK.

Application filed September 13, 1922. Serial No. 588,054.

To all whom it may concern:

Be it known that I, HERBERT T. HERR, a citizen of the United States and a resident of Philadelphia, in the county of Philadelphia and State of Pennsylvania, have invented a new and useful Improvement in Nozzle Blocks, of which the following is a specification.

My invention relates to nozzle box structures for elastic-fluid turbines and it has for its object to provide a nozzle block which shall be made in sections so that the nozzle passages may be constituted by complementary grooves or passages in inclined end faces of the sections, whereby the sections may be produced by forging or die-casting processes, thereby making it possible to manufacture nozzle structures economically, and to build up nozzle blocks of adjustable sizes from sections carried in stock.

Apparatus made in accordance with my invention is illustrated in the accompanying drawings, forming a part of this application, in which: Fig. 1 is a detail sectional view of a turbine showing my improved nozzle block structure applied thereto, the section being taken in part along the line I—I of Fig. 2; Fig. 2 is a plan view, from the underside, of my improved nozzle construction; and Fig. 3 is a sectional view along the line III—III of Fig. 1.

In the drawings, I show a nozzle box 10, to which is secured a nozzle block 11 and a sector of stationary blades or buckets 12, carried by a suitable member 13 bolted to the box. A blade carrying disk 14 is provided with first and second rows of blades or buckets 15 and 16, the blades or buckets 15 being arranged between the nozzle block 11 and the sector of stationary blades or buckets 12 so as to be acted upon by motive fluid received from the nozzle passages 17 of the nozzle block. The second row of moving blades 16 is acted upon by motive fluid discharged by the stationary blades or buckets 12. It is to be understood, however, that the blading referred to is by way of example only; and that, in so far as my invention is concerned, any suitable blading may be employed with my improved nozzle structure.

My invention consists in an improved type of nozzle block structure so that it may be readily produced by relatively economical manufacturing processes, such as

forging or die-casting and so that it may be made of any suitable size. To this end, I make the nozzle block structure 11 in a plurality of sections 18 which have front and back faces 19 and 20 and inclined end faces 21 and 22, the latter faces being respectively provided with grooves or passages 23 and 24, which, when the sections are assembled, constitute the nozzle passages 17, aforesaid. A nozzle structure to meet different requirements may be readily built up by choosing the proper number of sections.

The sections 18 are preferably provided with upper and lower edges or flanges 25 and 26 at the front faces thereof for attachment to the nozzle box 10, the upper flange or edge being preferably held in place by the holding means for the stationary blade or bucket carrier 13.

From the foregoing, it will be apparent that, by making the nozzle block in sections and by providing the nozzle passages in the faces of the sections, I have produced a nozzle block which may be more expeditiously and economically manufactured, as by drop-forging or die-casting processes, than may be produced by processes in common practice, such as casting and finishing. Also, as the size of the nozzle structure may be varied merely by the number of sections used, it will be apparent that the cost of turbine manufacture may be materially reduced and more prompt service afforded for the reason that, with a single turbine and a quantity of nozzle sections in stock, a turbine of any given capacity within its limits, may be produced merely by choosing the number of nozzle sections corresponding to the capacity desired.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:—

1. The combination with a nozzle box, of a sectional nozzle block structure comprising pairs of abutting members having complementary grooves or passages on adjoining faces constituting nozzle passages, said ad-

joining members being secured directly to the nozzle box.

2. The combination with a nozzle box, of a nozzle block structure comprising pairs of abutting sections having end faces inclined with respect to the front and back faces thereof, the adjoining end faces being provided with complemental passages or grooves to constitute nozzle passages, each 10 of said sections being attached directly to the nozzle box.

3. The combination with a nozzle box, of a plurality of nozzle block members having flanges for attaching directly to the box and 15 being provided with inclined end faces hav-

ing complemental grooves or passages to constitute nozzle passages.

4. A turbine comprising blading, a nozzle box and a nozzle construction including pairs of abutting members secured directly to the nozzle box and having complemental 20 passages on adjoining faces of the members constituting nozzle passages, whereby, with the blading, a turbine of a desired capacity may be produced by using a suitable number of sections. 25

In testimony whereof, I have hereunto subscribed my name this 6th day of September 1922.

HERBERT T. HERR.
